CLAIM

The ornamental design for an embossed basin as shown and described.

DESCRIPTION

FIG. 1 is a perspective view of an embossed basin showing the design.

FIG. 2 is a front elevation view thereof;

FIG. 3 is a right side elevation view thereof;

FIG. 4 is a left side elevation view thereof;

FIG. 5 is a rear elevation view thereof;

FIG. 6 is a perspective view thereof;

FIG. 7 is a front elevation view thereof, showing an emphasized portion A;

FIG. 8 is an enlarged cutting section perspective view of the emphasized portion A from FIG. 7; and,

FIG. 9 is a top plan view thereof.

The broken lines depict environmental structure or subject matter that forms no part of the claimed design.

1 Claim, 8 Drawing Sheets
